ROOFING ELEMENT

Application filed June 3, 1927. Serial No. 196,158.

This invention relates to improvements in roofing elements, and more particularly to shingles of the flexible type generally referred to as prepared asphalt shingles. These shingles are in very common use at the present time and are generally fabricated from felted fibrous sheets, impregnated with asphalt and coated with a layer of waterproofing material, which coating has applied thereon to and partially imbedded therein any suitable surfacing material such as crushed slate or the like.

When shingles of the type referred to are assembled on a roof, their inherent flexibility renders the exposed portions thereof liable to be raised by the force of the wind from contact with the underlying shingle element, so as to permit rain and snow to be driven along the surface of the underlying element and into contact with the roof boards or other supporting structure, resulting in deterioration of the latter.

Numerous expedients have been suggested for interlocking shingles of this type so as to hold the exposed portions thereof flat against the underlying surface. In general, however, these devices are either inefficient from the standpoint of actual protection afforded to the roof, or they include auxiliary fasteners secured to the shingle and requiring additional procedure in the manufacture thereof, or they are adapted to be used in connection with separate securing means which must be nailed to the roof structure and otherwise manipulated during the operation of laying the shingles in assembled relation on the roof.

An object of the present invention is to provide a shingle having means for effectively holding the butt thereof in a flatwise position against the underlying elements.

Another object of the invention is to provide a shingle with such holding or locking down means, without the use of auxiliary fastening elements.

Another object is to provide a shingle having interlocking provisions which function additionally to facilitate the proper alignment and spacing of the elements in the several courses.

The foregoing objects are attained in the several embodiments of the invention which are presently to be described, by forming the shingle with interlocking means including a retrovertible tip, an edge of which is adapted to abut and contact with a portion of an edge of the adjacent underlying shingle so as to prevent displacement of the tip from its normal operative retroverted position.

In the accompanying drawings:

Figure 1 is a fragmentary view, in plan, of a portion of a roof showing the manner in which shingles of several courses are assembled and interlocked.

Figure 2, is a vertical section taken along line 2—2 of Figure 1,

Figure 3 is a similar section taken along line 3—3 of Figure 1,

Figure 4 is a fragmentary perspective showing a modified form of a shingle embodying my invention.

Figure 5 is a similar view, showing a further modification of the invention, and

Figure 6 is a plan view showing how the form of the shingle shown in Figure 1 may be cut from a sheet of roofing material with the minimum amount of waste.

Referring now in detail to Figure 1, the numeral 10 indicates generally one form which the shingle of my present invention may take. The shingle is of substantially rectangular outline, but is adapted to be laid in what is known as the point-down fashion, that is, with its diagonals disposed horizontally and vertically of the roof. When viewed in this position the shingle 10 may be said to comprise two upper side edges 11 and 12, and two lower side edges 13 and 14. The horizontally opposed corners 15 and 16 of the shingle are formed with shoulders 17 and 18 respectively, extending laterally therefrom for a purpose to be hereinafter pointed out.

These shoulders are each defined by upper edges 19 and lower edges 20, extending substantially parallel to the horizontal diagonal of the shingle, and by a vertical edge 21, extending substantially parallel to the vertical diagonal line of the shingle. The lower edges of these shoulders join the edges 13 and 14 of the shingle as shown, while the upper edges 100

19 of the shoulders are connected to the edges 11 and 12 by the upwardly directed edges 22, as shown. In this way the shingle is provided with right angular notches 24, which are adapted to function as keepers for the reception of a locking extension formed on the lower end of the shingle as presently to be described.

The downwardly directed corner of the shingle is adapted to have its tip turned back or under-folded into a retroverted position, to embrace the shoulders of the adjacent pair of underlying shingles in the preceding course. This corner of the shingle is preferably formed with a pair of ears 30 and 31, extending laterally of the converging edges 13 and 14, and having any desired configuration, although by preference I show them of an arcuate shape. Extending forwardly of these ears 30—31 is a constricted neck portion 32, terminating in an enlarged locking head or extension 33, having a substantially rectangular configuration. This corner of the shingle is adapted to be folded under along the dotted line 34, connecting the points 35—36, at which the ears 30—31 join the respective edges 13 and 14 of the shingle. This operation of folding back the corner of the shingle may be carried out in any convenient manner, and forms no part of my present invention. It is desirable however, to perform this operation at the factory, and package the shingles with the corners in their under-folded position. Obviously however, suitable instrumentalities may be provided on the roof and the folding operation performed immediately prior to laying the shingles. For economy of production, however, and in order to save time on the roof, the folding operation is best carried out during the manufacture of the shingle at the factory.

It is to be noted that the shingle with its shoulders and locking extensions already described should be so dimensioned that the distance between the line of fold of the tip and the edges 37 of the locking extension 33, is greater than the height of the shoulders 17 and 18, and that the width of said extension 33 is less than the horizontal distance between the opposed edges 22 of a pair of adjacent shingles when these are in position.

In laying the shingles it will be apparent to one skilled in the art, that each course is laid with the vertical edge 21 of a shoulder 17 on one shingle in substantial abutment with the vertical edge 21 of a shoulder 18 on the adjacent shingle in the same course. The shingles of this course are then nailed at a point inwardly of the lower extremities of the marginal edges 11 and 12. Each shingle of the succeeding course is then applied by inserting the tip thereof underneath a pair of underlying contacting shoulders 17—18 while holding the body of the shingle in a position away from the roof, and then moving

the shingle bodily upwardly until the line of fold contacts with the aligned edges 20 of the shoulders. The locking extension is then manipulated so as to deflect the same along the neck 32 on a line substantially parallel to the edges 37, and into the locking recess 24 and substantially in the plane of the underlying course as clearly shown in Figures 2 and 3, so that the edge 37 thereof will lie contiguous to the aligned edges 19 on the underlying shoulders. Instead of providing for engagement of the edges 37 and 19 throughout their extents as aforesaid, it may be desirable to effect the interlocking engagement with only a portion of said edges in contact. In such case, therefore, the end portions of the extension 33 could be bent or curved upwardly into a position where said edges will contact only at certain points along said edges. In any event however, the main body of the shingle is then folded backwardly into position against the roof and nails driven through the shingle inwardly of the lower extremities of the marginal edges 11 and 12 thereof. Thus the alignment and proper spacing of the shingles is very easily accomplished, and an effective interlocking of the shingles of the several courses is provided. It will be seen that the shoulders 17 and 18 overlapping the retroverted tip of the overlying shingle, will hold the latter in place and that outward movement of the retroverted tip of the overlying shingle is prevented by the engagement of the edges 37 on the extensions 33 thereof with the upper edges 19 of the locking shoulders 17 and 18, on the underlying adjacent shingles. Thus displacement of the locking extensions is avoided and consequently any tendency for the exposed portion of the shingle to be raised or blown up by the wind is eliminated.

The ears 30 and 31 which I provide in the preferred embodiment of the present invention, are adapted to contact with the underside of the shingles in the preceding course as shown in Figure 1, and thus provide additional contacting area by which the retroverted tip is properly held in place by the shingles of the underlying course. These ears however, are an optional expedient and need not in all cases be employed. Thus, I have shown in Figure 4, a modified form of the invention in which these ears are eliminated. As will be apparent, this form of shingle is characterized by the same locking means as shown in Figure 1, but does not provide the additional contacting area between the under-folded tip and the adjacent shingles which is realized when the shingle is formed with the ears 30 and 31.

In Figure 5, I have shown another modification in which the locking extension is formed at its extremities with prong-like projections 40 and 41 instead of with straight edges 37, as in Figure 1. These projections

40 and 41 can be so proportioned as to adapt them to being hooked over the edges 19 into a position overlying the locking shoulders to thereby prevent forward or outward movement of the tip.

Referring now to Figure 6, I have indicated one manner in which the form of the invention shown in Figure 1 may be cut from a sheet of roofing material with a minimum of waste.

The sheet is indicated at A, one marginal edge thereof being shown in dot and dash lines as at A', while the other edge is similarly shown at A². As this sheet is led through suitable cutting mechanism it is slit along spaced series of broken lines indicated as a whole at 60, and corresponding in outline to the connected marginal edges of the ears 30, neck portions 31 and locking extension 33. The sheet is also formed with series of spaced parallel slits 70, extending at an angle to the margin of the sheet as shown, and with series of slits 80 extending at right angles to each of the slits 70. The slits 80 extend from a point midway of the slits 70 to a point midway of the portion 61 of the broken line slit 60. The cutting of the individual elements from the sheet may then be completed by severing the sheet along lines 90 and 95, extending, respectively, transverse and lengthwise of the sheet, and connecting the adjacent termini of slits 60 and 70.

Thus, it will be noticed the cutting operation may be carried out in such manner that the tip of each shingle is complementary, in part, to the shoulders of two other shingles, and is composed of material cut from the margins of these two other shingles so as to provide one of the locking shoulders in each of the latter, the other locking shoulder in each of said shingles being similarly cut so as to supply material for the formation of the tip of another shingle. It will also be noticed that the slits 70 each define the top edge 25 of one shingle and the edges 20 of the shoulders of adjacent units cut from the sheet.

The extended portions 65 remaining above the material forming the shoulders 17 and 18 of each shingle and representing the material removed in forming the neck portions 32 of an adjacent intervening shingle, may be removed in any desirable manner, by die punching or cutting through the same either before or after the shingles are finally severed from each other and from the sheet.

The modified forms of the shingle shown in Figures 4 and 5, may be cut from the sheet in a manner similar to that described, as will be apparent to those skilled in the art without further explanation.

In any event however, the peculiar configuration which these shingles take necessarily results in the wastage of a relatively insignificant amount of material along the margins of the sheet, as shown.

Having described in rather full detail the nature of my invention, it should be apparent that these details need not be strictly adhered to but that various changes and modifications may readily suggest themselves to those skilled in the art, without departing from the principles of the invention, as defined by the appended claims.

I claim as my invention:

1. A flexible roofing unit comprising a retrovertible tab having a locking extension, said extension having an edge engageable with a rearwardly facing edge of a unit previously laid, the line of contact between said edges being spaced from the line of retroversion of said tab.

2. A flexible roofing element comprising a retrovertible locking tab having portions thereof adapted to lie in the plane of an underlying unit previously laid, said tab also having portions adapted to contact with a rearwardly facing edge of said underlying unit, said rearwardly facing edge being spaced from the line of retroversion of said tab and overlaid by said tab-carrying element.

3. A flexible roofing unit having one corner thereof retrovertible into a position embracing a portion of a unit previously laid, said retrovertible corner having an extension adapted to lie in the plane of said previously laid unit, and said extension having portions adapted for contact with an edge portion of said previously laid unit at points confined within the exposed marginal edges of the first named unit.

4. A flexible roofing unit having a retrovertible flap at one of its corners, said flap including laterally extending ears, and laterally extending shoulders spaced from said ears by a constricted neck portion, the corners of said unit adjacent to the first named corner being formed with side-wise extensions, the upper edges of which are adapted to be in contact with the downwardly directed edge of the shoulders of the adjacent unit in an overlying course, whereby to retain the flap of said overlying unit in its retroverted interlocked position.

5. A flexible roofing unit substantially square in shape and having a retrovertible tab at one of its corners and lateral extensions at the adjacent corners, the retrovertible tab having indentations spaced from the line of retroversion of the tab so as to provide aligned shoulders, said tab being adapted to embrace adjacent extensions of a pair of similar units laid in the preceding course and to be deflected into the plane of said extensions, whereby said shoulders will contact with the upper edges of said extensions to restrain said tab from displacement.

6. A flexible roofing unit having a retroverted tab at one of its corners, said tab being notched at its lateral edges at points

spaced from the line of retroversion of said tab so as to present, when the unit is in place with its tab in operative position on a roof, downwardly directed edges entirely overlaid
5 and concealed by the exposed portions of said unit, each of said edges being adapted for abutting contact with an upwardly directed edge of an adjacent unit in the preceding course, whereby to prevent dislodgment of
10 said tab from its retroverted position.

7. A flexible roofing unit of substantially square shape, having a retrovertible flap at one of its corners and side-wise extensions at the immediately adjacent corners, said flap
15 comprising a narrow neck spaced from the line of retroversion of the flap, and formed with laterally directed shoulders at the extremity thereof, said shoulders having downwardly directed horizontal edges adapted
20 for edge contact with upwardly directed horizontal edges on the side-wise extensions of adjacent similar units in a previous course.
